BOTTLE-CARRYING TRAY

Henry I. Richards, Arlington, Va.

Application August 25, 1944; Serial No. 551,219

14 Claims. (Cl. 224—45)

1

This invention relates generally to bottle-carrying trays and particularly to a tray adapted to be used in the ordinary manner or with a mechanical apparatus for loading and dispensing bottles, etc., forming the subject matter of another application Serial No. 549,046, filed Aug. 11, 1944.

The principal object of the present invention is to provide a bottle-carrying tray of novel construction which may be expeditiously loaded or unloaded.

Another important object of the present invention is to provide a bottle-carrying tray having compartment-forming fingers so arranged as to be removed from between a plurality of bottles when the normally abutting carrying handles are separated to permit manual ejection of bottles from one end of the tray.

It is a further object of the invention to provide a bottle-carrying tray of simple though rugged construction which is long wearing in use and economical in cost.

Other objects and advantages of the invention will become apparent during the course of the following description.

Although the present invention is suitable for use with all types of bottles and other articles and packages, for convenience, a milk bottle-carrying tray is herein shown for illustrative purposes only.

In the drawings I have disclosed one embodiment of the present invention.

In this embodiment:

Figure 1 is a plan view of the tray comprising the invention, parts of the carrying handles being broken away;

Figure 2 is a view in end elevation looking from the left in Figure 1;

Figure 3 is a vertical sectional view taken on the line 3—3 of Figure 1;

Figure 4 is a view in side elevation showing a plurality of milk bottles positioned therein, and

Figure 5 is a plan view of the bottle-carrying tray when positioned on the supporting bar of a mechanical loading apparatus.

Referring now to the drawings, numeral 10 designates the floor of the tray comprising the present invention, which may be stamped from sheet metal or molded from a plastic or other material so as to be provided with a pair of upstanding sides 12 and a pair of downwardly extending end portions to form a pair of transversely extending feet 14 and 16. It will be noted that the front foot 16 is provided with an outwardly projecting flange 18 for a purpose to be described. The sheet

2

metal or other material from which the tray is stamped, formed or molded is chosen of a gauge or thickness sufficiently heavy so as to form a structure which will strongly support the load to be carried, normally eight filled milk bottles as shown. Each side 12 of the tray 10 has fixed thereto a plurality of spaced vertical rods 20, the upper ends of which are provided with eye portions 22.

A pair of tray handles 24 and 26 are pivotally mounted on the sides 12 by means of curved supporting members 28 and 30 also having eyes 25 at their lower ends. The eyes 25 and 22 receive rivet pins 27. The handle supporting members 28 and 30 have affixed thereto eye members 32 which rotatably support longitudinally extending rods 36. Each of the rods 36 is provided with a plurality of laterally inwardly extending fingers 38 which, together with a central longitudinally extending partition 40, divide the area of the tray 10 into two rows of bottle-receiving compartments. It will be noted that the partition fingers 38 adjacent the front end of the tray are of greater length than the balance of the fingers to completely close the front end of the tray when in a horizontal position.

The rear end of the tray is provided with a connecting bar 42 which is pivotally connected to the handle members 30 (Figure 2) as at 44 on handle 24 and at 46 on an extension 48 of handle 26. It will be obvious that movement of either handle 24 or 26 outwardly from the carrying position shown in Figure 3 will force the other handle to also move outwardly due to this pivotal connection.

A pair of small drums 50 are mounted on the ends of the rods at the rear of the tray 10. These drums 50 are connected by a flexible cable or band 52 secured at its extremities by suitable means to the peripheries of the drums. When the handles 24 and 26 are moved outwardly away from each other the flexible cable 52 will force drums 50 to rotate oppositely about the rods 36 and thus move the partition fingers 38 upwardly and outwardly in the direction of motion of handles 24 and 26. Due to the chosen diameters of the drums 50 the fingers 38 will rotate upwardly with somewhat greater speed than the handles 24 and 26 to insure that the fingers are outwardly of the vertical lines of the sides 12 of the tray 10. This permits bottles to be loaded into or ejected from the tray 10 without interference from the fingers 38 when the handles 24 and 26 are in fully opened position, Figure 2 disclosing the handles 24 and 26 in partially opened position.

In order that the fingers 38 may return to the horizontal positions shown in Figures 1, 3 and 4, a pair of springs 54 are mounted on the rods 36 so as to urge counter rotation of the drums 50 upon closing of the handles 24 and 26 to return the fingers 38 to horizontal position and maintain the flexible cable 52 in a taut condition at all times.

The floor of the tray 10 is provided with a pair of longitudinally extending slots 56 each intermediate one side of the tray and the central partition 40. These slots receive a pair of upstanding bottle-ejecting pieces 58 projecting through the slots 56 and connected to each other beneath the tray by an intermediate portion 60. The connecting piece 60 is provided with a centrally located depending flange 62 forming a thumb piece to effect movement of the ejecting pieces 58. In order that the ejectors 58 may be operated without binding throughout the length of the slots 56, the thumb piece 62 is provided with an opening 64 through which a rod 66 extends. The ejectors 58 are supported by and may be smoothly slid along the rod 66 which is supported at its ends in the downwardly turned leg portions 14 and 16.

The ejectors 58 may be readily installed within the slots 56 by twisting them so as to permit insertion therethrough and subsequently twisting the ejectors back to the position shown or by making the ejectors readily detachable from the supporting and connecting bar 60 by the use of screws, nuts, bolts, etc.

The advantages of the bottle-carrying tray comprising the present invention will be apparent from the following description of its use.

Where the milk bottle-carrying tray 10 is used in connection with bottle-ejecting mechanism of the type partially illustrated in Figure 5 and which forms no part of the present invention, the front tray leg 16 is inserted behind a bar 70 extending transversely in front of and spaced from a shelf 72 having a plurality of rows of milk bottles thereon. The forwardly turned flange 18 of the leg 16 is then hooked under the bottom of shelf 72 to support the bottle-carrying tray 10 and its two rows of bottles in aligned relationship with a pair of bottle-receiving rows 76 on the shelf 72.

The tray 10 and its two rows of bottles is properly aligned with a pair of bottle-receiving rows on shelf 72 (Figure 5) by sliding the tray laterally on the supporting bar 70 until the ejector guide rod 66 drops into one of a plurality of notches 78 provided in alignment with each of a plurality of bottle-ejecting rods 80 having bottle compartment-forming fingers 82. As shown in the figure, the compartment fingers 82 have been pivoted upwardly so as to permit milk bottles to be ejected from the tray 10 into the empty rows 76 on the shelf 72.

It will now be apparent that the delivery man may manually slide the thumb piece 62 along the rod 66 to cause the ejector pieces 58 to simultaneously deliver the two rows of milk bottles from the tray onto the shelf 72. Thereafter, the bottle-ejecting fingers 82 on the shelf 72 are rotated back to horizontal position as shown in the lower left hand portion of Figure 5. Conversely, bottles may be ejected from the shelf 72 by the rod 80 and its fingers 82 onto the tray 10 as desired, the partition fingers 38 being thrown upwardly out of the way upon opening of the handles 24 and 26, and the ejectors 58 acting as stops for each row of four bottles. If the tray is used with-

out the ejectors, stops may be formed in or struck up from the material forming the tray.

Whether milk bottles are being moved to or from the tray 10, it is first positioned upon the supporting bar 70 in the manner described. The handles 24 and 26 are then opened together with their partition fingers 38 to a substantially horizontal position so that both handles and fingers fully clear the sides 12 of the tray 10 to permit the ejection or reception of bottles to or from the tray 10 without interference. After the tray 10 has been loaded or unloaded the handles 24 and 26 are swung back together in a vertical position as shown in Figure 3 and the tray is then lifted from the supporting bar 70.

In the event that the milk bottle-carrying tray 10 is not used in conjunction with the milk dispensing apparatus illustrated in Figure 5, the tray is loaded in the normal manner by simply inserting 8 bottles of milk therein. Upon arrival at the point at which one or more of the milk bottles are to be left, the handles are swung open and the thumb piece 62 is operated to eject from the end of the tray the desired number of bottles or they are merely lifted from the tray.

It will now be apparent that the milk bottle-carrying tray comprising the present invention is highly advantageous and time-saving when used in conjunction with the milk bottle dispensing apparatus disclosed and equally advantageous when not used therewith. Obviously, while the bottle-ejecting mechanism provided therewith is highly advantageous in the rapid delivery of milk bottles, this tray may also be used in the normal manner. The tray is simply but strongly and ruggedly constructed so as to have long life at low initial cost and may readily be manufactured from non-critical materials.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A tray comprising rigid sheet material having upwardly turned edge portions forming sides and downwardly turned end portions forming supporting feet, a pair of handles mounted on the upper edge portions of said sides, said handles being pivotally mounted to facilitate loading and unloading of said tray, and a bar connecting said handles to effect simultaneous motion thereof toward and away from tray-carrying position.

2. A device for carrying bottles comprising a tray including sides, a pair of handles mounted on the upper edge portions of said sides, a longitudinally extending rod mounted on one of said handles for axial rotation, and a plurality of laterally extending fingers fixed to said rod and defining bottle-receiving compartments with said sides.

3. A device for carrying bottles comprising a tray including sides, a pair of handles mounted on the upper edge portions of said sides, a longitudinally extending rod mounted on one of said handles for axial rotation, a vertical longitudinally extending partition integrally mounted on said tray and defining bottle-receiving rows with said sides, and a plurality of laterally extending fingers fixed to said rod and dividing said rows into bottle-receiving compartments.

4. A device for carrying bottles comprising a

tray including sides, a pair of handles pivoted to said tray, a longitudinally extending rod mounted on at least one of said handles, a plurality of laterally extending fingers fixed to said rod and defining bottle-receiving compartments with said sides, and a bar connecting said handles to effect simultaneous motion thereof toward and away from tray-carrying position.

5. A device for carrying bottles comprising a tray including sides, a pair of handles pivoted to said tray, a longitudinally extending rod mounted for rotation on each of said handles, a plurality of laterally extending fingers fixed to said rod and defining bottle-receiving compartments with said sides, a bar connecting said handles to effect simultaneous motion thereof toward and away from tray-carrying position, and means for effecting rotation of said rod and fingers upon pivotal movement of said handles.

6. A device for carrying bottles comprising a tray including sides, a pair of handles pivoted to said tray, a longitudinally extending rod mounted for rotation on each of said handles, a plurality of laterally extending fingers fixed to said rod and defining bottle-receiving compartments with said sides, and means for effecting rotation of said rod and fingers upon pivotal movement of said handles.

7. A device for carrying bottles comprising a tray including sides, a pair of handles pivoted to said tray, a longitudinally extending rod mounted for rotation on each of said handles, a plurality of laterally extending fingers fixed to said rod and defining bottle-receiving compartments with said sides, and means for effecting rotation of said rod and fingers upon pivotal movement of said handles, said means comprising a drum fixed to each of said rods, flexible means connecting and being wound partially about said drums to effect rotation of said fingers upon movement of said handles from carrying position, and spring means connecting said rod and said handles to effect return of said fingers to normal horizontal position upon reverse movement of said handles to tray-carrying position.

8. A device for carrying bottles comprising a tray having sides and open ends, a pair of handles each pivotally connected to one of said sides, and a plurality of laterally extending fingers mounted on one of said handles to define a plurality of individual bottle-receiving compartments with said sides and to close one of said ends, said fingers being rotatable away from said bottles upon separating movement of said handles.

9. A device for carrying bottles comprising a tray having sides and open ends, a pair of handles pivotally connected to said sides, a plurality of laterally extending fingers mounted on at least one of said handles to define bottle-receiving compartments with said walls and close said ends, said fingers being rotatable out of the path of said bottles upon separating movement of said handles, and a bar connecting said handles to effect simultaneous motion thereof toward and away from tray-carrying position.

10. A device for carrying bottles comprising a tray including sides, a pair of handles pivoted to said tray, a longitudinally extending rod mounted for rotation on each of said handles, a plurality

of laterally extending fingers fixed to said rod and defining bottle-receiving compartments with said sides, and means for effecting rotation of said rod and fingers upon pivotal movement of said handles, said means comprising a drum fixed to each of said rods and flexible means connecting and being wound partially about said drums to effect rotation of said fingers upon movement of said handles from carrying position.

11. A device for carrying bottles comprising a tray having sides and open ends, a pair of handles pivotally connected to said sides, and a plurality of laterally extending fingers and mounted on at least one of said handles to define bottle-receiving compartments with said walls and close said ends, said fingers being rotatable with respect to said handles and out of the path of said bottles upon separating movement of said handles.

12. A bottle-carrying tray for cooperation with the spaced tray-supporting bar of the shelves of bottle dispensing apparatus comprising rigid sheet material having a flat bottle-supporting area and upwardly turned edge portions forming sides and downwardly turned end portions forming supporting feet, one of said end portions being insertable between said bar and said shelf and provided with an outwardly projecting flange to engage the bottom of said shelf to maintain the tray in loading or unloading position.

13. A bottle-carrying tray for cooperation with the spaced tray-supporting bar of the shelves of bottle-dispensing apparatus comprising rigid sheet material having a flat bottle-supporting area and upwardly turned edge portions forming sides and downwardly turned end portions forming supporting feet, one of said end portions being provided with an outwardly projecting flange extending parallel to said area and spaced therefrom a distance equal to the depth of the forward end of said shelf, said end portion being insertable between said bar and said shelf to engage the bottom of the latter to maintain the tray in loading or unloading position.

14. A bottle-carrying tray for cooperation with the spaced tray-supporting bar of the shelves of bottle dispensing apparatus comprising a tray portion having sides, and end members forming supporting feet, one of said end members being insertable between said bar and said shelf and provided with a flange to engage the bottom of said shelf to maintain the tray in loading or unloading position.
